a corporation of New York

Application July 14, 1934, Serial No. 735,244

15 Claims. (Cl. 51—143)

This invention relates to an improvement in polishing machines and more particularly to machines of the type having an abrasive belt serving as the polishing medium.

The invention is primarily directed to a machine for polishing sheet or flat material through the use of a continuously moving abrasive or polishing belt in conjunction with adjustable and reliable pressure means which holds the belt in contact with the material. Prior to this invention, many kinds of machines have been developed for use in polishing flat material. In some instances a narrow abrasive belt was provided and the material, to be polished, moved back and forth in a plane perpendicular to the direction of travel of the belt. Such a machine, applied to polishing sheet steel, while removing the rough blemishes from the steel as it came from the rolling mill, could not produce the scratch free surface desired. Another type of machine in use utilized a wide belt and required a power driven roller to be moved into contact with the steel to be polished. This roller was not only unwieldy but entirely incapable of following any uneven surfaces of the sheet of steel and in consequence it was necessary to grind off the high spots before the low spots could be reached by the belt to be polished. By reason of the belts used in these machines as well as the lack of flexibility of the machine itself, great difficulty was encountered in preventing some of the abrasive material from becoming ground into the surface of the steel by the moving belt and thus producing scratches which could not readily be removed. The belts for these machines were necessarily constructed of canvas or other heavy fabric coated with a suitable abrasive and were extremely costly. When the abrasive surface of a belt of this type became worn, it was either necessary to purchase a new belt or the user was required to recoat the old belt. This latter procedure, although less costly, was unsatisfactory since it was impossible to provide a uniform abrasive coating on the belt in a manner employed by the belt manufacturer.

The present invention has been designed to produce a satisfactory polish on sheet steel, thus overcoming the above mentioned difficulties and has for its principal objects first, to provide an abrasive belt of sufficient width to simultaneously polish the full width of a given sheet of steel; secondly, to provide a pair of power driven rollers on which the abrasive belt is carried; third, to provide a belt pressure roller, generally midway between the power driven rollers, which is ver-

tically adjustable to produce a variable pressure contact of the belt with the steel; fourth, to support this roller in such a manner that it may pivot longitudinally about a transverse axis and may have a slight upward yield under spring tension when an unusually high spot on some part of the steel is contacted or when the carriage on which the steel is supported has reached the end of its travel in one direction and is being reversed; fifth, the provision of a further roller substantially midway of the power driven rollers and above the pressure roller which is movable to increase or decrease the tension of the belt as well as to cause said belt to properly track upon the power driven rollers; and sixth, the provision of power driven rollers, the support for which being such that, upon release of the tensioning roller, a worn belt may be quickly removed and replaced without altering or disassembling any part of the machine. Other objects and advantages of the invention will be more fully understood from a consideration of the following specification taken in conjunction with the accompanying drawings and in which,

Figure 1 is a side elevation of a machine embodying one form of this invention;

Figure 2 is a plan view of the structure shown in Figure 1;

Figure 3 is an enlarged view of the pressure and tension rollers taken substantially on the line 3—3 of Figure 1;

Figure 4 is an enlarged vertical sectional view taken substantially on the line 4—4 of Figure 3 and shows yieldable supporting means and a quick release operator for the pressure roller;

Figure 5 is a fragmentary view similar to Figure 4 showing the method of displacing the pressure roller and abrasive belt from contact with the work at the end of the travel in one direction of the work supporting carriage;

Figure 6 is a fragmentary vertical sectional view of the bearing support for the pressure roller;

Figure 7 is a fragmentary sectional view of the pivotal support of the quick release lever;

Figure 8 shows means for locking the release lever to retain the pressure roller in elevated position;

Figure 9 is an enlarged fragmentary view partly in section showing the method of adjustment of the tensioning roller by which to cause the belt to track on the power driven rollers; and

Figure 10 is a fragmentary view of one of the power driven rollers, being taken substantially on the line 10—10 of Figure 2.

Reference is now had generally to Figure 1 of the drawings which discloses a machine bed on which is mounted a longitudinally movable carriage. A sheet of steel is secured in any suitable manner to this carriage. Above the carriage a vertically adjustable frame is located on which are supported parallel rollers arranged on axes at right angles to the length of the bed. A suitable power unit is connected with one of the rollers which in turn is connected with the other roller in order that both of said rollers will have synchronous power drive. Somewhat below and between the driven rollers is a pressure roller which is mounted in a horizontal guide to facilitate removal at one side of the machine and replacement by a new roller or buffering roller. This roller is so mounted that it is vertically adjustable toward or away from the carriage and is so connected to its support that it may pivot longitudinally about an axis perpendicular to its axis of rotation. The support for this roller is also provided with spring means which permits a slight upward yield of the roller during certain conditions of use. A tensioning roller, preferably directly above the pressure roller, is mounted on a vertically adjustable support and is also capable of longitudinal pivoting about a transverse axis. The frame on which all of the rollers are supported is designed to permit mounting a belt upon the rollers without disassembling any of the rollers or any other part of the machine. When the belt is so mounted, the tensioning roller is adjusted to take up the slack of the belt and the pressure roller adjusted to cause the belt to contact with the steel to be polished. By reason of the use of a pair of driven rollers and a pressure roller therebetween, an inexpensive paper abrasive belt is entirely satisfactory and since these belts are readily removable and replaceable, the possible more frequent replacement thereof constitutes no loss of time in use of the machine as compared with other machines requiring partial disassembly to remove and replace the belt.

The reference numeral 10 is employed to designate a polishing machine embodying one form of the invention. The machine includes a bed 11 suitably elevated from the floor on posts 12. Formed in the bed is a track upon which is located a longitudinally movable carriage 14. The support for and mechanism by which the carriage 14 is reciprocated is conventional and therefore forms no part of the invention. Projecting upwardly from adjacent one side of the bed is a supporting frame 15. This frame has a vertical face formed with guides 16. Against this face and interfitting with the guide 16 is a roller supporting frame 17 which projects from the member 15 horizontally over the central portion of the bed 11. The frame 17 includes a central portion 18 to opposite sides of which are secured roller supporting yokes 20 and 21 by means of bolts 22. The yoke 20 has a central portion 24 which terminates in spaced arms 25. Suitable bearings are provided in the ends of the arms to support the shaft 26 of one of the belt driving rollers 27. It will be noted that the shaft 26 projects through and beyond both arms 25, having a gear or sprocket 29 keyed to one end and a pair of V-pulleys 30 keyed to the other. The gear 29 is connected in any suitable manner as by a chain 32 with a power source in the form of an electric motor 33 which may be supported on a separate base or an offset arm joined to the base 11. The yoke 21 is also provided with

suitable bearings to support a roller 35 on a shaft 36. One end of the shaft 36 projects through and beyond the yoke and is fitted with a pair of V-pulleys 37. The pulleys 30 and 37 of the rollers 27 and 35 are connected by two V-belts 38. Thus power transmitted from the motor 33 to the roller 27 is also conveyed to the roller 35 providing the machine with a pair of synchronous belt-carrying driven rollers.

Mounted on the central portion 18 of the frame 17 is a fixture 40 which is formed with a guide block 41. The block 41 is engaged by a further block 42 to which is attached the support for a belt tensioning roller 44. The support includes a yoke 45, the arms 46 of which are provided with bearings in which to receive the ends of the shaft 48 on which the roller 44 is mounted. Centrally of the yoke 45 there is a depending bracket 50 through which an opening is made to receive a bolt 51. The bolt 51 projects into the block 42 and serves to support the yoke 45 for pivotal movement. The bracket 50 is continued in an arm 53 which projects downwardly and terminates in an enlarged portion 54 provided with an opening 55 therethrough. Mounted in the opening 55 is a short shaft 57 which is provided with an opening 58 perpendicular to the shaft axis. The opening 58 in the shaft registers with concentric and enlarged openings 59 in the portion 54. Secured to or forming a part of the block 42 is a bracket 61 having an opening 62 therethrough. A shaft 63 projects through the opening 62 and is fitted with a collar 64 adjacent the bracket 61. Beyond the collar 64 the shaft 63 is threaded and projects through one opening 59 to have threaded engagement with the walls of the opening 58 in the shaft 57. The shaft 63 continues outwardly of the portion 54 through the second opening 59. The enlarged portion 66 of a shaft 67 is secured to the end of the shaft 63 opposite the collar 64. Shaft 67 terminates in a wheel or knob 68. As heretofore mentioned, the roller 44 serves not only to increase or decrease the tension of an abrading belt which passes over the driven rollers 27 and 35 but also is adapted to align the belt causing it to properly track upon these rollers. Thus the roller 44 must be tiltable about an axis perpendicular to its axis of rotation. In Figure 3 of the drawings the extreme positions of tilt of the roller 44 are shown. This tilting is accomplished by rotating the knob 68 which causes the shaft 57 to be moved lengthwise of the threaded shaft 63, thus swinging the arm 53 about the bolt 51 and tilting the roller supporting yoke 45.

Projecting upwardly into a threaded opening in the block 42 is a shaft 70. This shaft continues downwardly through a fixed frame 71 and terminates in a beveled gear 73. Mounted on the portion 18 is a pair of brackets 74 and 75 in which is supported a shaft 76. One end of the shaft 76, projecting beyond bracket 75, is fitted with a beveled gear 77 which meshes with the gear 73. The other end of the shaft 76 is provided with a wheel 79 on which is located a knob 80. As heretofore mentioned, the entire mounting for the roller 44, which includes yoke 45 and block 42, is vertically adjustable of the guide block 41. Rotation of the wheel 79 causes beveled gears 77 and 73 to rotate, thus rotating shaft 70 which, by reason of its threaded engagement with the block 42, moves said block upwardly or downwardly of the guide block 41.

Beneath the frame 17 and substantially centrally between rollers 27 and 35 is a pressure roll-

er 86 which is mounted on a shaft 87. This shaft is formed with end recesses 88 to receive combined thrust and supporting bearings 89. These bearings are preferably enclosed in the recess by 5 caps 90. An opening in each cap permits entrance of the supporting shaft 92 into the bearing 89. Externally of the roller shaft 87, the shaft 92 is formed with an enlarged threaded portion 93 which engages the threads of an opening 94 formed in the arm 95 of a yoke 96. The threads of the portion 93 are cut away to provide a smooth surface 98 for contact with a set screw 99 mounted in the arm 95. The structure above described is adjustable to properly support the roller 86. Withdrawal of the set 10 screw 99 and rotation of the shaft 92 projects the enlarged portion 93 thereof inwardly or outwardly of the arm 95 of the yoke 96 to give proper rotating freedom to the shaft 87. The portion 93 projects beyond the outer face of the arm 95 and is formed with a threaded opening 101, into the walls of which a plurality of slots 102 are cut. The outer surface of this end of the portion 93 is of reduced size and receives an anti-friction bearing 103. This bearing is secured to the portion 93 by threading a stud 104 into the opening 101 causing the walls adjacent the slots 102 to be expanded into contact with the inner race of the bearing 103. A wheel 106 is mounted on the bearing 103 and serves with a corresponding wheel at the other end of the yoke 96 to elevate the roller 86 under conditions and for a purpose hereinafter set forth.

Secured to the underface of the central portion 18 of the frame 17 in any suitable manner as by studs 109 is a bracket 110. The bracket is formed with a pair of transverse openings 111 which are spaced by a central web 112. Formed centrally of the web 112 is an opening 113 which is concentric with an opening 114 formed in the portion 18. A further opening 116 is made in the web 112 which connects the openings 111 of the bracket. This opening is in the form of a slot and receives a pinion gear 117. A worm gear 118 mounted on a shaft 119 projects into one of the openings 111 of the bracket 110 to engage the teeth of the gear 117. The shaft 119, exteriorly of the bracket 110, is supported in journals 121 which are connected and supported by the bracket 110 through arms 122 secured by studs 123. Adjacent the clear side of the portion 18 of the frame 17 is a downwardly directed flange 125 to which may be secured a plate 126. The shaft 119 projects through the plate 126 and is fitted with a wheel 127 having a knob 128.

The gear 117 has a centrally located threaded opening 130. Projecting through the opening 130 is a shaft 131. This shaft is threaded throughout its length and engages the threads of the opening 130. An opening 133 is made longitudinally of the shaft. The lower end of this opening is enlarged to form a pocket 134. Projecting through the opening 133 in the shaft 131 is a rod 135. The lower end of this rod is formed or fitted with a collar 136 provided with flanges to form an annular recess 137 about the rod 135. At the meeting of pocket 134 with opening 130, a shoulder 138 is formed and between this shoulder and the base wall of the recess 137, a spring 140 is located. This spring is of the compression type and encircles the rod 135, serving to urge the rod downwardly of the shaft 131.

In order that the rod may not be moved out of the opening of this shaft, the upper end is formed with a threaded portion 141 with which is en-

gaged a collar 142 that normally rests upon the upper end of the shaft 131. The portion 141 has threaded connection with an extension 144 for the rod 135. The upper end of this extension is formed with a slot 145 to which is joined, by 5 means of a pivot pin 147, a lever 148. This lever is of a length to extend to one side of the machine, being terminated in a convenient handle 149. On the portion 18 (see Figures 4, 5 and 7) is a support 151 for the lever 148 which includes 10 an upwardly opening slot 152 for receiving the lever. A suitable pin 153 serves to pivotally connect the lever with the support. The lower end of the support is formed with an annular opening 155 into which projects the enlarged threaded 15 end 156 of a shaft 157. A collar 158 has threaded engagement with the end 156 of the shaft, being rotatable to move the support 151 upwardly of the shaft or to permit it to move downwardly thereon. The lower end of the shaft 157 is 20 threaded into the portion 18 of the frame 17. As will more fully be understood from a further description of the invention, the lever 148 is for the purpose of raising the rod 135 upwardly of the shaft 131 against tension of the spring 140. 25 To increase or decrease the extent of upward shifting of the rod 135 by means of the lever 148, the collar 158 is rotated upwardly or downwardly to change the elevation of the lever support 151.

The lower end of rod 135 terminates in a portion 160 having a transverse opening 161 there-through. A frame 163, having an upstanding pivot portion 164, receives the portion 160, being pivotally engaged therewith by means of a bolt 35 165 which projects through suitable openings 166 in the support 164 and the opening 161 in the portion 160. The frame 163 comprises a body portion from which depend parallel flanges 167. These flanges are undercut to provide a guide- 40 way 168. The yoke 96 which supports the pressure roller 86 is provided with an overcut, along the base wall thereof, to permit being inserted into the guideway 168. When the yoke 96 is thus mounted in the frame 163, one or more set 45 screws 170 mounted in said frame are rotated to lock the yoke in place. It will be understood that the pivotal support for the frame 163 and yoke 96 is such that the roller may move end- 50 wise about a transverse pivot in the form of bolt 50 165 for the purpose of following any uneven contour of a sheet of steel to be polished.

The movable carriage 14, on which a sheet of steel is secured in any suitable manner, is formed with side members 171, in the outer vertical faces 55 of each of which a longitudinal recess or groove 172 is made. Across the face of the groove 172 are plates 173 which provide a restricted opening 174 into said groove 172. A pair of trip members 175, having inclined surfaces 176, are located ad- 60 jacent the side members 171, being fixed to plates 177. Each plate is formed with a slot 178 through which a bolt 179 projects. The head 180 of the bolt is located in the groove 172 seating against the inner faces of plates 173. The bolt 179 projects through the restricted opening 174 and is fitted with a nut 181. The plate 176 is vertically adjustable of a bracket 182 by means of a threaded shaft 183 which, when rotated by the knob 184, projects the plate 176 and trip members 175 upwardly. When the desired adjustment of the height of the trip has been obtained, the nut 181 is rotated to lock the entire structure in place. Inasmuch as the groove 172 extends the full 75

length of the carriage, the trip members 173 may be adjusted to any desired location.

An abrading belt 185 is mounted on the rollers 27 and 35. Between these rollers the belt is supported above and beneath by the tension roller 44 and pressure roller 86. It is apparent that when the belt is properly tensioned by vertical adjustment of roller 44, roller 86 serves to engage the belt with the sheet of steel to be polished. 10 When a sheet of steel or other material is fastened in any suitable manner to the carriage 14, polishing may commence. The trip members 175 are adjusted lengthwise of the bed to positions adjacent the ends of the sheet. When the carriage 15 14 travels toward its limits of movement in one direction, the members 175 are moved toward the roller 86 and wheel 106. At precisely the end of travel of the carriage in one direction, members 175 are projected under the wheels 106 causing 20 said wheels to ride up on to said members thus raising the roller 86 and releasing the pressure of the belt 185 upon the sheet of steel. It will be understood that the upward movement of the roller 86 is under tension of the spring 140 and that when the carriage moves in the opposite direction, the members 175 are withdrawn from beneath the wheels 106 thus allowing the roller 86 to again press the belt into contact with the sheet to be polished. Although there is only a short 25 period of time when the carriage is not moving at the end of its travel in one direction or another, pressure contact of the belt during this short period will tend to burn the material adjacent the end. To eliminate this objection as well as to prevent additional wear on the belt, the trip members 30 35 are provided.

It will be understood that the tension roller 40 44 serves to increase or decrease tension of the belt 185 as well as to cause it to track upon rollers 27 and 35, the former being accomplished by rotation of wheel 79 and the latter by rotation of the wheel or knob 68. The pressure roller 86 is also vertically adjustable through rotation of the wheel 127. This vertical adjustment in no 45 way alters the tension of the spring 140 since said spring and its support are a part of the unit which is vertically adjustable. During the process of polishing sheet steel, it frequently occurs that particles of abrasive from the belt or other 50 foreign matter drop onto the sheet. Should the belt come in contact with these particles it would produce scratches in the surface of the sheet which could not be readily removed. A means therefore is provided by which to relieve the 55 pressure contact of roller 86 upon the belt in the quickest manner and without stopping the machine. This has been accomplished through the provision of the lever 148 which, being available at one side of the machine, may be depressed to 60 raise the roller 86 against the tension of spring 140, permitting the sheet of steel with the foreign matter thereon to travel harmlessly past. To withhold pressure contact of the belt 185 through roller 86 without altering the pressure adjustment by rotation of wheel 127, means in the form of a latch 186 is provided to secure the lever 148 in depressed position. This latch includes a 65 swivel base 187 secured to the portion 18 of the frame 17. A rod 188 projects upwardly from the base 187 to support the latch which is adjustable vertically thereof by rotation of nuts 189.

It is contemplated that when a higher polish than that obtainable with an abrading belt is desired, the belt may be removed, roller 86 removed, and a buffing roller substituted therefor.

The buffing roller is in a yoke similar to the yoke 96 which supports roller 86 and may be rotated by a direct drive motor which would be located approximately where the wheel 106 is now located or a V-pulley which would be driven by a belt connected with one of the rollers 27 or 35. 5

Although applicant has shown and described only one modification of means for supporting and controlling a fully flexible roller by which to cause an abrading belt to contact with the surface of a sheet of material to be polished, means for releasing the tension of this roller, and other structural advantages shown and described, it will be understood that modifications or other adaptations of these structures is contemplated in so far as such modifications may lie within the spirit and scope of the invention as set forth in the hereunto annexed claims. 10 15

Having thus set forth my invention what I claim as new and for which I desire protection 20 by Letters Patent is:—

1. In a machine for polishing flat material, a polishing belt, a roller in contact with said belt, means mounting said roller for free and unrestrained movement about an axis perpendicular to its axis of rotation, means supporting said mounting means, said latter means being adapted to adjust said roller to contact said belt with the material to be polished, and further means for releasing said roller from operative adjustment independently of said supporting means. 25 30

2. In a machine for polishing flat material, a pressure roller, means including resilient support for said roller, said means being adapted to adjust said roller toward or away from said material, and means for releasing said roller from operative adjustment, said latter means being operable independently of the means supporting said roller. 35

3. In a machine for polishing flat material, a polishing belt, a pressure roller in contact with said belt, means sustaining said roller for movement about an axis perpendicular to its axis of rotation, further means supporting said roller through said sustaining means, said further means being movable to adjust said roller to contact said belt with the material to be polished, and means operable independently of said further means for releasing said roller and said belt from operative adjustment with respect to 50 said material. 40 45

4. In a machine for polishing flat material, a polishing belt, a roller in contact with said belt, a yoke supporting said roller, a frame, slidably interfitting parts on said yoke and said frame, 55 said parts facilitating removal and replacement of said roller, means sustaining said frame for movement about an axis perpendicular to the axis of rotation of said roller, and further means mounting said sustaining means on said machine. 60

5. In a machine for polishing flat material, a polishing belt, a roller in contact with and adapted to advance said belt to engage said material, a supporting member on said machine having an opening, a shaft in said opening, means in 65 said member supporting said shaft, said means being manually operable to move said shaft in said opening, a rod projecting through an opening in said shaft, yieldable means connecting said rod with said shaft, a frame sustaining said roller, said frame being joined to said rod whereby manual operation of said means advances said roller. 70

6. In a machine for polishing flat material, a polishing belt, a roller in contact with said belt, 75

- a supporting member on said machine having an opening, a shaft in said opening, means in said member supporting said shaft, said means being operable to move said shaft longitudinally of said opening, further means having yieldable connection with said shaft, a frame sustaining said roller, said frame being pivotally joined to said further means, said first means being adapted to move said roller and contact said belt with the material to be polished, and said further means being operable independently of the shaft operating means whereby to release said roller and said belt from operative adjustment with respect to said material.
5. In a machine for polishing flat material, a polishing belt, a roller in contact with said belt, a supporting member on said machine having an opening, a shaft in said opening, a gear in said member having threaded engagement with and supporting said shaft, manually operable means for rotating said gear and advancing said shaft upwardly or downwardly of said opening, a rod projecting through an opening in said shaft, means for preventing relative movement of said rod and said shaft in one direction, and spring means permitting relative movement of said shaft and said rod in the other direction, a frame sustaining said roller, said frame being pivotally joined to said rod whereby, upon manipulation 25 of said manually operable means, said roller may be yieldingly advanced to contact said belt with the material to be polished.
6. In a machine for polishing flat material having a continuous polishing belt, a roller in contact with said belt, a separable yoke and frame sustaining said roller, a rod in said machine, pivotal means connecting one end of said rod with said frame to permit movement of said roller about an axis perpendicular to its axis of rotation, a supporting member on said machine having a vertically movable shaft, said shaft having an opening through which said rod projects, and yieldable means connecting said rod with said shaft whereby movement of said shaft in one direction relative to said supporting member causes said roller to yieldingly contact said belt with the material to be polished.
7. In a machine for polishing flat material having a continuous polishing belt, a roller in contact with said belt, a supporting member on said machine having an opening, a shaft in said opening, means in said member supporting said shaft, said means being operable to move said shaft longitudinally of said opening, a rod projecting through an opening in said shaft, a separable yoke and frame sustaining said roller, said frame being pivotally connected with said rod, means causing said rod to move with said shaft in one direction, further means causing said rod to yieldingly move with said shaft in the opposite direction, a lever on said machine connected with said rod, said lever being operable to move said rod relative to said shaft whereby to release said roller and said belt from polishing position with respect to said material.
8. In a machine for polishing flat material having a continuous polishing belt, a roller in contact with said belt, a separable yoke and frame sustaining said roller, a rod in said machine, pivotal means connecting one end of said rod with said frame to permit movement of said roller about an axis perpendicular to its axis of rotation, a supporting member on said machine having a vertically movable shaft, said shaft having an opening through which said rod projects, and yieldable means connecting said rod with said shaft whereby movement of said shaft in one direction relative to said supporting member causes said roller to yieldingly contact said belt with the material to be polished.
9. In a machine for polishing flat material having a continuous polishing belt, a roller in contact with said belt, a supporting member on said machine having an opening, a shaft in said opening, means in said member supporting said shaft, said means being operable to move said shaft longitudinally of said opening, a rod projecting through an opening in said shaft, a separable yoke and frame sustaining said roller, said frame being pivotally connected with said rod, means causing said rod to move with said shaft in one direction, further means causing said rod to yieldingly move with said shaft in the opposite direction, a lever on said machine connected with said rod, said lever being operable to move said rod relative to said shaft whereby to release said roller and said belt from polishing position with respect to said material.
10. In a machine for polishing flat material having a polishing belt, a reciprocable carriage supporting the material to be polished, a roller in contact with said belt, means sustaining said roller, a supporting member on said machine, yieldable means in said supporting member for advancing said roller to contact said belt with the material on said carriage, adjustable trips mounted on said carriage adjacent the ends of said material, said trips being engageable with means on the roller supporting yoke, when said carriage has completed its travel in one direction, to raise said roller and said belt from off said material.
11. In a machine for polishing flat material having a polishing belt, a roller in contact with said belt, means sustaining said roller, further means on said machine supporting said sustaining means, both of said means having yieldable connection to permit upward movement of said roller and said roller sustaining means relative to said further means, a reciprocable carriage on said machine, automatically operable trip means on said carriage and said roller sustaining means for raising said roller and said belt from polishing position when the direction of movement of said carriage is being reversed.
12. In a polishing machine having a material receiving carriage, a horizontally disposed frame overlying said carriage, a pair of rollers, opposed yokes on said frame supporting said rollers, said rollers projecting laterally beyond said yokes and above and beneath said frame and said yokes, means for rotating one of said rollers, and further means connecting said rollers for synchronous rotation, said frame, yokes and roller rotating means being located within the space defined by a belt mounted on said rollers.
13. In a machine for polishing flat material having a polishing belt, an adjustably mounted roller in contact with said belt, said roller being movable to advance said belt into polishing position, a reciprocable work supporting carriage on said machine, means on said carriage operable to raise said roller and relieve said belt from polishing position when the direction of movement of said carriage is being reversed.
14. In a machine for polishing flat material having a polishing belt, an adjustable roller in contact with said belt, said roller being movable to advance said belt into polishing position, a reciprocable carriage on said machine, automatically operable trip means on said carriage and said roller for raising said roller and relieving said belt from polishing position when the direction of movement of said carriage is being reversed.
15. In a machine for polishing flat material having a polishing belt, a roller in contact with said belt, means sustaining said roller, wheels mounted on said sustaining means, a reciprocable work receiving carriage on said machine, trip members on said carriage, said wheels being in the path of said trip members and movable thereover to raise said roller and relieve said belt from polishing position when the direction of movement of said carriage is being reversed.

ALFRED V. BREED.
